Nelson M. Howard

UNITED STATES PATENT OFFICE.

FREDERICK M. FURBER, OF REVERE, MASSACHUSETTS, ASSIGNOR TO UNITED SHOE MACHINERY COMPANY, OF PATERSON, NEW JERSEY, A CORPORATION OF NEW JERSEY.

WELT-LAYING MACHINE.

1,208,769.

Specification of Letters Patent. Patented Dec. 19, 1916.

Application filed May 29, 1915. Serial No. 31,180.

To all whom it may concern:

Be it known that I, FREDERICK M. FURBER, a citizen of the United States, residing at Revere, in the county of Suffolk and State 5 of Massachusetts, have invented certain Improvements in Welt-Laying Machines, of which the following description, in connection with the accompanying drawings, is a specification, like reference characters on the 10 drawings indicating like parts in the several figures.

This invention relates to machines for laying welts, rands and similar strips and is herein illustrated in connection with a 15 welt laying machine of the general type shown in United States patent to McLeod No. 957,987.

In the manufacture of shoes, particularly those known as McKay, it is sometimes the 20 practice to provide a mock or imitation welt on the margin of the upper surface of the sole in order to give the shoes an appearance more desirable to the trade. Hitherto it has been customary to prepare the welt, for example, by notching one edge of it as shown 25 in United States patent to Arnold No. 646,592, so that the welt may conform readily to the curvature of the edge of the sole and may be laid flat without the formation 30 of folds or puckers which would otherwise occur, particularly around the toe portion of the sole.

The general object of the present invention is to provide a machine by which a 35 plain welt may be smoothly laid and thereby to do away with the necessity which has heretofore existed for slitting, notching or similarly operating upon the inside edge of the welt prior to using it in a welt laying 40 machine.

One feature of the invention comprises, in a machine of the class described, means for applying a welt to a sole and means for removing during the laying operation the 45 puckers which form where the welt is bent or turned. This and other features of the invention including certain details of construction and combinations of parts will be described in connection with an illustrative 50 machine and pointed out in the appended claims.

Referring now to the accompanying drawings—Figure 1 is a front elevation of a machine in which the present invention is

embodied, the machine being equipped with 55 a pounder for removing the puckers; Fig. 2 is a detail perspective showing a modified form of pounder in process of removing the puckers in the inside edge of the welt as said welt is being laid around the toe portion of the sole; Fig. 3 is a perspective 60 similar to Fig. 2 but showing a knife in place of the pounder.

Mounted in fixed bearings in the frame of the machine is a shaft 1 to the outer end 65 of which is fast a feed wheel 3 and to the inner end a gear 5 said latter gear being rotated through a gear 7 by a so-called "hand-belt-power drive," the details of which are not shown since they form no part of the 70 present invention. It will be sufficient to point out that the gear 7 is rigid with a friction disk 9, that the continuously driven pulley 11 is loose on the stud 13, that said pulley has a friction face adapted to co-operate with the adjacent face of the friction disk, and that by turning the handle 15 the pulley may be forced against the disk with a controllable amount of pressure, 75 the pull of the driven belt 17 aiding the 80 operator.

The gear 5 meshes with a gear 19 fast to a hollow shaft 21 upon the outer end of which the laying wheel 23 is fast, said hollow shaft being mounted in a casting 25 85 which is pivoted at 27 to the frame of the machine and is urged downwardly about said pivot by a spring 29. A screw bolt 31 determines the lower limit of movement of the casting 25 and hence of the laying wheel 90 23, and a treadle rod 33 provides means to lift the wheel 23 when desired to facilitate the insertion of the work. An edge gage 35 and welt guide 37 insure that the welt shall be laid along the edge of the sole. The 95 machine, as thus far described, is similar to the machine of the McLeod patent and its details of construction will not be further described.

Extending through the hollow shaft 21 is 100 a solid shaft 39 to the outer end of which is fast a pucker-removing and welt-smoothing tool 41 herein shown as a pounder having a substantially oblong contour except that the ends are somewhat rounded. Fast to the 105 inner end of the solid shaft 39 is a small pulley 43 which may be driven continuously in any suitable manner one face of said

pulley being held against a roll 45, the axis of which is fixed, by a coiled spring 47, said spring being located between a collar 49 on the shaft 39 and a shoulder on the hollow 5 shaft 21. That face of the pulley 43 which contacts with the roll 45 is provided with depressions one of which is shown at 51 with the result that the shaft 39 and pounder 41 are reciprocated as they are rotated. A 10 shield 53 partially incloses the wheel 23 and pounder 41 to protect the operator from possible injury.

In the operation of the machine the end of a piece of welting, which is supplied in a 15 coil and mounted near the machine on a reel (not shown), is drawn through the guide 37 and laid on the margin of a sole. The treadle rod 33 is then moved downwardly to separate the wheels 23 and 3, the 20 sole and welt pushed between the wheels, and the treadle rod released. The operator then turns the crank 15 with one hand and guides the sole with the other. As the sharply curved toe portion of the sole is 25 reached, puckers form or start to form in the inside edge of the welt; and these puckers are removed and the welt smoothed and beaten down by the pounder 41, the combined reciprocatory and rotatory movement 30 of the pounder facilitating this desirable result. The direction of rotation of the pounder is opposite to that of the wheel 23 so that a more effectively smoothing action on the welt is secured than would otherwise be 35 the case.

In Fig. 2 a modified form of tool 53 for removing the puckers is shown, said tool being a pounder of general elliptical outline, the plane of the ellipse being inclined obliquely to the axis of the shafts 21 and 39.

In Fig. 3 the tool for removing the puckers is shown as a knife of a generally cylindrical shape, having two semicircular blades 55 the height of each of which increases gradually from its forward end (with reference to the direction of rotation) to its rear end. In the figure the arrow indicates the direction of rotation of the knife, and it will be seen that the effect is to shave off the puckers as fast as they are formed or start to form whereas, when the pounders are used, the puckers are beaten down flat.

It should be noted that all three tools have a rubbing action on the welt and act to 55 smooth the welt as well as to remove the puckers or prevent their formation. It should be understood that the welting is usually skived so as to present a thin inner edge and that the face of the welting which 60 is to contact with the sole carries a coating of cement so that the welt, when laid, will adhere to the sole.

Although the invention has been described in connection with a machine for laying a 65 welt on a sole it should be understood that

the invention is not limited in the scope of its application to the particular machine shown and described.

Having thus described my invention, I claim as new and desire to secure by Letters 70 Patent:

1. A machine of the class described, having, in combination, means for laying a welt on a sole, and means for removing, during the laying operation, the puckers which 75 form where the welt is bent or turned.

2. A machine of the class described, having, in combination, means for laying a welt progressively along the margin of a sole, and means for similarly removing the puckers 80 which form in said welt at the toe portion of said sole.

3. A machine of the class described, having, in combination, means including a wheel for laying a welt progressively along the 85 margin of a sole, and means located at one side of said wheel for removing the puckers which form where the welt is bent or turned.

4. A machine of the class described, having, in combination, means including a wheel for laying a welt progressively along the margin of a sole, a pucker removing member located at one side of said wheel, and means for rotating said member. 90

5. A machine of the class described, having, in combination, means including a wheel for laying a welt progressively along the margin of a sole, a pucker removing member located at one side of said wheel, means for 100 rotating said member, and means for reciprocating said member.

6. A machine of the class described, having, in combination, means including a rotary wheel for laying a welt progressively 105 along the margin of a sole, a member located at one side of said wheel and adapted to remove the puckers formed in said welt as it is laid around the toe portion of said sole, and means for rotating said member in a direction opposite to the direction of rotation of said wheel. 110

7. A machine of the class described, having, in combination, means for laying a welt on a sole, a pounder for removing the puckers which form when the welt is bent around the margin of the toe portion of the sole, and means for operating said pounder. 115

8. A machine of the class described, having, in combination, means for laying a welt 120 on a sole, a pounder for removing the puckers which form when the welt is bent around the margin of the toe portion of the sole, and means for rotating said pounder.

9. A machine of the class described, having, in combination, two wheels between which the welt and sole are gripped and by which said welt and sole are fed, a hollow shaft on which one of said wheels is mounted, a shaft located inside said hollow shaft, 125 130

a pucker-removing and welt-smoothing tool fast to said last-named shaft, and means for rotating said shafts.

10. A machine for laying a welt on a sole, having, in combination, a wheel arranged to support the sole by engaging the margin of the under side thereof, a welt laying wheel

and a smoothing tool arranged to engage the upper surface of the welt, and means for operating said wheels and tool.

10 In testimony whereof I have signed my name to this specification.

FREDERICK M. FURBER.
